JOHN STURROCK, OF CHICAGO, ILLINOIS, ASSIGNOR, BY MESNE ASSIGNMENTS, TO
INTERNATIONAL HARVESTER COMPANY, A CORPORATION OF NEW JERSEY.

PITMAN CONNECTION FOR MOWERS.

1,314,717.

Specification of Letters Patent. Patented Sept. 2, 1919.

Application filed April 7, 1917. Serial No. 160,488.

To all whom it may concern:

Be it known that I, JOHN STURROCK, a subject of the King of Great Britain, residing at Chicago, in the county of Cook and State of Illinois, have invented certain new and useful Improvements in Pitman Connections for Mowers, of which the following is a full, clear, and exact specification.

My invention relates to pitman connections for mowers.

The object of the invention is to provide means whereby wear between the pitman and the associated and coöperating parts of the mower is automatically compensated for and the parts at all times are held in proper adjustment.

A further object is to provide means for easily and quickly connecting and disconnecting the pitman to the mower parts co-operating therewith.

These objects are attained by the use, in connection with pitman jaws or straps, of controlling members by means of which the jaws may be clamped; further, by the use of controlling members by means of which the jaws may be spread; and still further, by the use of controlling members for clamping or spreading the jaws at the will of the operator.

In the drawings I have for purposes of illustration shown specific embodiments which my invention may assume in practice.

In these drawings, wherein corresponding reference characters indicate like parts throughout the several views—

Figure 1 is a top plan view of the preferred form of my pitman;

Fig. 2 is a side view of the pitman shown in Fig. 1, the device being shown in its inverted position;

Fig. 3 is a plan view of a modified form of pitman connection; and

Fig. 4 is a side elevation of the device shown in Fig. 3.

Considering first the jaw controlling means shown at the grassward end of the pitman, I have illustrated three positions of the elements, these elements being shown in their jaw closing position in full lines and in their jaw releasing and opening positions in dotted lines. To clearly distinguish the elements in their dotted line positions, I have used the same reference characters employed for the full line position, but have employed dotted lead lines where these ref-

erence characters indicate the elements in their dotted line positions. I will now describe in detail the specific embodiments of my device as shown in the drawings.

The grassward end of the body portion 10 of the pitman, preferably made of wood, has secured thereto by means of bolts 9, two resilient jaws 11 and 12, and these jaws are provided with registering slots 13, the extremities of which are indicated by reference characters 14 and 15. Slidable in these registering slots, is a flat substantially fork-shaped automatic take-up and jaw opening member 16 having inner inclined bearing surfaces 17 which contact with and co-operate with similarly inclined bearing surfaces 18 on the outer portions of the cup-shaped bearings 19 on the outer ends of the resilient jaws 11 and 12. The outer surfaces of the member 16 are inclined, as 70 indicated at 20, and coöperate, as will be hereinafter described, with the inclined end walls 14 of the slots 13 in the jaws 11 and 12. The member 16 has an integral stubble-wardly extending shank 21 which is encircled by a spring 22, one end of which bears against the shoulder 23 at the stubble-ward end of the inclined surfaces 20. The other end of the spring bears against a curved end portion 24 of a bell crank member 25, said curved end portion being apertured and loosely carried by the pin 26 which secures the curved portion 24 against displacement thereon. The bell crank member 25 is journaled at its opposite end on a 85 crank 27 mounted between the resilient jaws 11 and 12 and provided with trunnions 28 and 29 journaled in said jaws. Integral with the trunnions 29, is an arm 30, whereby the crank and bell crank member may be manually operated. The crank 27 is inclined or offset relative to the plane of the arm 30, as clearly shown in Fig. 1, and when the jaws 11 and 12 are clamped or closed, the force of the spring 22 is exerted in a line passing 100 through the end 24 of the bell crank 25 and the opposite end of said bell crank journaled on the crank 27. From an inspection of the showing in Fig. 2, it will therefore be seen that the force of the spring 22 tends to maintain the crank 27, bell crank 25, and member 16 in their jaw closing position, a toggle action being obtained. The bell crank member 25 is also provided with laterally extending lugs 31, which limit inward. 110

movement of the bell crank 25 and maintains it in the position shown in full lines in Fig. 2.

In the controlling means shown in Figs. 3 and 4, it will also be noted that the shank 21, which is integral with the jaw opening member 16, is slidably mounted in the grassward end of the body portion 10 of the pitman and is normally forced outwardly by means of the spring 22 mounted thereon. It will also be seen that the operating mechanism for the jaw closing and opening member 16 is slightly different from that above described and consists in a longitudinally curved link 32 provided at its grassward end with a hook 33 and pivoted at its stubbleward end on a lever 34. The lever 34 is apertured at 35 and when in operative position is mounted on a stud 36 rigidly attached to the body portion 10 of the pitman. The link 32 is offset or curved at a point adjacent its pivotal connection with the lever 34 in such a manner that when the lever is swung to jaw opening position, the offset or notch in the link will receive the stud 36, and in this position the pivotal connection between the lever and link will be located in a plane below a line drawn through the grassward hooked end of the link 32 and stud 36. Thus it will be seen that the spring 22 (Figs. 3 and 4) will maintain the lever 34 in jaw opening position until the lever is manually displaced.

Referring now to jaw controlling means shown as applied to the opposite or stubbleward end of the pitman, it will be seen that this form is embodied in an automatic take-up for the journal box carried by the crank pin. The pitman 10 has secured thereto by means of bolts 38 straps 37 which are similar to the resilient jaws 11 and 12 and are provided on their stubbleward ends with conical bearing surfaces 39. These bearing surfaces are apertured to receive a slotted clamping bolt 40, by means of which the bearing box 41, which is provided with corresponding conical bearing surfaces 42, is secured between the conical surfaces 39 of the straps 37. Said bearing box 41 is of hollow construction and carries the usual oil cup shown at the extreme right in Figs. 1 and 2. Integral with one of the straps 37, are lugs 43, between which is guided the shank 44 of a wedge-shaped take-up member 45, which latter extends through the slot in the clamping bolt. Mounted upon the shank 44 on the grassward side of the lugs 43, is a spring 46 which bears at one end against the lugs 43 and is secured against displacement at the other end by the cotter pin 47.

I will describe first the operation of the automatic take-up and jaw opening member 16 on the grassward end of the pitman. Referring to Fig. 1, the member 16 is shown in full lines with the jaws 11 and 12 clamp-

ing the spherical bearing surfaces of the knife head. In this position the end 24 of the bell crank member 25 compresses the spring 22, and the spring acting against the stubbleward end of the jaw closing member 16, constantly tends to force said member grassward and maintain the jaws in closed position, thereby automatically compensating for the wear on these parts. In order to open the jaws, the arm 30 is swung upwardly to the position shown in dotted lines at the right in Fig. 2, in which position the member 15 is released from the action of the spring 22, the end 24 of the bell crank lever being forced against the pin 26 on the shank 21, and the jaws are partially opened. In order to force the jaws to their wide open position to release the knife head, the arm 30 is swung to the position shown at the left in Fig. 2 in dotted lines, when the crank 27, through the bell crank 25, pulls the shank 21 and member 16 stubblewardly, and the bearing surfaces 20 coöperate with the inclined bearing surfaces 14 at the inner end of the slots 13 and force the jaws 11 and 12 outwardly to the extreme outward position.

Referring now to the structure shown in Figs. 3 and 4, the jaws are normally maintained in closed position by the spring 22, which acts between the grassward end of the pitman 10 and the member 16 to force the latter in a grassward direction and close the jaws. To open the jaws, the lever 34 is fulcrumed on the stud 36 and is swung rearwardly, forcing the member 16 against the tension of the spring 22 and opening the jaws in the manner above described.

In order to assemble the parts at the stubbleward end of the pitman, the jaws 37 are sprung apart and the bearing box 41 is mounted thereon between the conical bearing surfaces 42. The clamping bolt 40 is then inserted through the conical bearing surface 39 and the apertured grassward end of the bearing box 41. The wedge-shaped member 45 is then inserted in the slot in clamping bolt 40 by first passing therethrough the shank 44 of said wedge-shaped member, said shank being then positioned between the bearing lugs 43. The spring 46 is then placed on the grassward end of said shank and is compressed sufficiently to allow the cotter pin 47 to be inserted through the grassward end of said shank and maintain the spring under tension.

It will be clear from the above description that I have provided simple and efficient devices for taking up the wear of the associated and coöperating parts at both ends of the pitman and that the devices are of such a nature that they may be cheaply manufactured and easily and quickly assembled. Moreover, as has been fully pointed out, the pitman connection for the grassward end may be manually and easily operated to

grasp the co-operating part of the knife head and may also be positively actuated to release said knife head.

While I have for purposes of illustration 5 described certain specific forms which my invention may assume in practice, it will be clear that the same is capable of many other modifications and that such changes and modification may be made without departing 10 from the spirit of the invention as expressed in the appended claims.

What I claim as new and desire to secure by Letters Patent is:

1. In a pitman connection, a pitman having 15 resilient jaws provided with inclined exterior bearing surfaces thereon, and means for clamping said jaws including a longitudinally reciprocable member having inclined bearing surfaces co-operating with the bearing surfaces on said jaws, the bearing surfaces on said reciprocable member being shiftable from the inside to the outside of said jaws.

2. In a pitman connection, a pitman having 25 resilient jaws, a longitudinally reciprocable member for clamping said jaws, resilient means for actuating said member in one direction, and lever mechanism for actuating said member in the opposite direction against 30 the tension of said resilient jaws.

3. In a pitman connection, a pitman having 35 resilient jaws provided with longitudinal slots therein, a longitudinally reciprocable jaw clamping member mounted between said jaws and extending through said slots, said clamping member having means co-operating with said jaws to press the same toward each other, and means for reciprocating said member in both directions.

4. In a pitman connection, a pitman having 40 resilient jaws provided with longitudinal slots therein, a longitudinally reciprocable jaw clamping member extending through said slots, said clamping member having means for pressing said jaws toward each other as said member is reciprocated, resilient means for advancing said clamping member to jaw clamping position and means for retracting said clamping members.

5. In a pitman connection, a pitman having 45 resilient jaws, and means including a reciprocable member for positively spreading said jaws.

55 6. In a pitman connection, a pitman having resilient jaws, and means including a reciprocable member carried by said pitman and operatively connected with said jaws for spreading the same.

60 7. In a pitman connection, a pitman having resilient jaws, a longitudinally reciprocable member carried by said pitman for spreading said jaws, and means for reciprocating said member.

65 8. In a pitman connection, a pitman hav-

ing resilient slotted jaws, a longitudinally reciprocable jaw spreading member carried by said jaws and extending through said slots, and means for reciprocating said member to spread said jaws.

9. In a pitman connection, a pitman having 70 slotted resilient jaws, a longitudinally reciprocable member carried by said jaws and extending through said slots, said member having outer inclined cam surfaces operatively associated with the walls of said slots whereby as said member is reciprocated the jaws are spread, and means for reciprocating said member.

10. In a pitman connection, a pitman having 75 resilient jaws, a longitudinally reciprocable jaw clamping member mounted between said jaws and having a shank portion, a spring carried by said shank portion, a lever carried by said pitman, and means carried by said lever and engaging said spring whereby said clamping member may be actuated by said lever to jaw clamping position.

11. In a pitman connection, a pitman having 80 resilient jaws provided with inclined elongated bearing surfaces thereon, and means engageable with said bearing surfaces for gradually clamping and for spreading said jaws.

12. In a pitman connection, a pitman having 85 resilient jaws with inclined bearing surfaces thereon, and a longitudinally reciprocable member having a plurality of bearing surfaces engageable with said inclined bearing surfaces on said jaws for clamping and for spreading the jaws.

13. In a pitman connection having resilient jaws, a reciprocable jaw clamping and spreading member, resilient means for actuating said member in one direction to clamp said jaws, and means for actuating said member in an opposite direction to spread said jaws.

14. In a pitman connection, a pitman having 100 resilient jaws, a longitudinally reciprocable jaw clamping and spreading member, and means including a crank mounted on said jaws for reciprocating said member.

15. In a pitman connection, a pitman having 105 resilient slotted jaws, a longitudinally reciprocable jaw clamping and spreading member mounted between said jaws and extending through said slots, a stubblewardly extending shank carried by said member between said jaws, resilient means for actuating said member in one direction, and means including lever mechanism for actuating said member in an opposite direction.

16. In a pitman connection, a pitman having 110 resilient slotted jaws, a longitudinally reciprocable jaw clamping and spreading member carried between said jaws and extending through said slots, a stubblewardly extending shank secured to said member between 115

5 said jaws, a spring carried by said shank, a bell crank lever loosely carried at one end of said shank and contacting with said spring, a crank arm carried by said jaws and pivotally connected to the opposite end of said crank lever, and means for actuating said crank arm.

10 17. In a pitman connection, a pitman having clamping jaws, one of which is resilient, a longitudinally reciprocable member for actuating said resilient jaw, resilient means for actuating said member in one direction, and lever mechanism for actuating said member in the opposite direction against the 15 tension of said resilient means.

18. In a pitman connection, a pitman having clamping jaws, one of which is resilient, a longitudinally reciprocable member carried by said pitman for forcing said resilient 20 jaw away from the remaining jaw, and means for reciprocating said member.

19. In a pitman connection, a pitman having resilient jaws, a longitudinally reciprocable jaw clamping member mounted between 25 said jaws and having a shank portion, a spring carried by said shank portion, a lever carried by said pitman, and a link member operatively connected to said lever and engaging said spring whereby said

clamping member may be actuated by said lever to jaw clamping position. 30

20. In a pitman connection, a pitman having clamping jaws, one of which is resilient, said resilient jaw being provided with elongated inclined bearing surfaces thereon, and means engageable with said bearing surfaces for moving said resilient jaw gradually toward and from said remaining jaw. 35

21. In a pitman connection, a pitman having clamping jaws, one of which is resilient, such resilient jaw being provided with inclined bearing surfaces thereon, and a longitudinally reciprocable member having a plurality of bearing surfaces engageable with the inclined bearing surfaces on said 45 resilient jaw to actuate said jaw toward and from the remaining jaw.

22. In a pitman connection, a pitman having clamping jaws, one of which is resilient, a reciprocable member adapted to actuate 50 said resilient jaw toward and from the remaining jaw, resilient means for actuating said member in one direction, and means for actuating said member in the opposite direction. 55

In testimony whereof I affix my signature.

JOHN STURROCK.
